TENNIS COURT MARKER

William H. Hann, Hackettstown, N. J.

Application September 22, 1943, Serial No. 503,349

2 Claims. (Cl. 91—12)

This invention relates to marking devices, and is particularly adapted to devices for marking tennis courts, roads, or any other surface where a line of a particular width and contour is desired.

An object of the invention is to provide a marker which will give an accurate line without overflow on the edges, which may be easily and simply guided in the desired direction.

A further object is to provide a marker in which the flow of material may be more readily and accurately controlled so that the operation of the device may be quickly started and stopped.

Other objects and advantages of the invention will appear as the description proceeds.

In the accompanying drawing—

Figure 1 is a side elevation showing my improved marker in use;

Fig. 2 is an enlarged side elevation;

Fig. 3 is an end view thereof;

Fig. 4 is a top plan view;

Fig. 5 is an enlarged view taken in the direction of the arrows 5—5 shown in Fig. 2;

Fig. 6 is a cross sectional view taken on the line 6—6 of Fig. 2 showing the marker in operative position;

Fig. 7 is a view similar to Fig. 6 showing the marker in inoperative position;

Fig. 8 is a perspective view of the controls.

In marking tennis courts or other surfaces it is desirable that the markings be accurate and along predetermined lines. Accordingly, I have provided a device which may be guided by a cord or cable stretched over the area to be marked. This cord or cable engages an arm which determines the path of movement of the device. I also provide a tank containing the marking fluid under pressure, a pair of nozzles, the direction of which is limited by marking shields.

In the accompanying drawing my marker 10 includes a tank 11 mounted by means of a band 12 on the wheels 13 and 14. The front end 15 of the tank 11 is removable and is held in place by means of the wing nuts 16 so that by removing the wing nut 16 the front 15 can be withdrawn for cleaning or filling purposes. Mounted on the front 15 is a bracket 17 in which is mounted the pivot 18 carrying the fork 19 and the castor wheel 20. Fastened to the fork 19 is an angle guide 21 which is slotted at 22 to engage a guide line 23. A pump 26 having an operating plunger 27 and an operating handle 28 is mounted on the side of the tank 11 to maintain pressure within the tank.

It will be seen that line 23 on the stanchions 55

24 and 25 may be set up over the area to be marked. Line 23 is engaged by slot 22 of the angle guide 21. The operator controlling the handle 28 will push the marker along the ground and the castor wheel 20 will pass over the area immediately under the guide line 23. Guide line 23 may be attached to stanchion 24, held by a pin 28 or preferably held by a stanchion such as 25 which consists of an angle member having a weighted portion 30 engaging the ground and adapted to hold the stanchion in an upright position. When marking a tennis court point 31 of the stanchion may be set behind peg 32 normally marking the court boundary.

15 At the bottom of the tank there are provided a plurality of nozzles 41 and 42 which preferably are set within a nozzle member 43 and have their open inner ends 45 covered by a valve member 46 mounted on the rod 41. Nozzle protecting 10 shields 48 and 49 are provided to prevent injury to the nozzles themselves and to define the area to be marked. The nozzles are preferably directed to cover an overlapping area as is shown in Fig. 6 so that an even flow of material is provided for the surface to be covered.

20 Shield members 50 and 51 are hinged at 52 and 53 respectively and are engaged by the arms 54 and 55 so that their movement on the hinges 52 and 53 are controlled by the position of these arms. Springs 56 and 57 tend to keep the shield members closed as shown in Fig. 7 when the operating lever 60 is free. The operating member 60 is fastened by means of a collar 61 to the pump 26. The operating lever 60 is adapted to be squeezed by the operator against the operating handle 28 to raise the shaft 62 against the spring 63 positioned by the rod 64 on the side of the tank 11. Shaft 62 pivoted at 65 to the U-shaped member 66 is fastened by the block 67 against the bottom of the tank. Mounted on the U-shaped member 66 is a shaft 68 pivoted to the rod 47 controlling the valve 46.

25 It will be seen that by gripping the handle 28 and the lever 60 the operator will not only open the plates 50 and 51 but will likewise open the valve 46 to allow the marking fluid to be discharged through the nozzles 41 and 42. Plates 50 and 51 clearly define the area to be marked and the position of the nozzles is such that fluid is sprayed across the entire area. By releasing the operating lever 60 the spring 63 causes the valve 46 to close and the springs 56 and 57 to bring the plate members together as shown in Fig. 7 to completely stop the flow of material.

30 It will be seen that I have provided a device

simple in operation containing a relatively few number of parts which will accurately mark lines along a predetermined line and which may be readily operated by one person. While my device is particularly adapted for use as a tennis court marker it can be applied to many different uses with minor adjustments.

I claim:

1. A marking device comprising a tank adapted to contain marking fluid, a plurality of nozzles on said tank, a valve for such nozzles, a pair of shield members pivotally mounted on the tank and adapted to enclose said nozzles when closed.

and to define the area to be marked when open, means for maintaining pressure within said tank and means for simultaneously opening or closing said shield members and said valve.

- 5 2. A marking device comprising a tank mounted for movement along a surface, a plurality of nozzles on said tank, a valve for said nozzles, a pair of shield members pivotally mounted on the tank and adapted to enclose said nozzles, spring means for normally holding said shield members in the closed positions, and an operating handle controlling said shield members and said valve.

WILLIAM H. HANN.
